UNITED STATES PATENT OFFICE.

CHARLES E. CATHER AND LOUIS H. BUCKLEY, OF WORCESTER, MASSACHUSETTS.

ENVELOP.

SPECIFICATION forming part of Letters Patent No. 705,036, dated July 22, 1902.

Application filed June 3, 1901. Serial No. 62,880. (No model.)

To all whom it may concern:

Be it known that we, CHARLES E. CATHER and LOUIS H. BUCKLEY, citizens of the United States, residing at Worcester, in the 5 county of Worcester and Commonwealth of Massachusetts, have invented a new and useful Improvement in Envelops, of which the following is a specification, accompanied by drawings forming a part of the same, in 10 which—

Figure 1 represents an envelop embodying our invention. Fig. 2 is an enlarged view of the metallic fastener by which the closing or seal-flap is attached to the body of the envelop. Fig. 3 shows the relation of the seal-flap to the bendable tongues of the fastener when the metallic eyelet is used. Fig. 4 shows the relation of the seal-flap to the bendable tongues of the fastener when the metallic eyelet is omitted, and Fig. 5 shows our 15 improved fastener with the seal-flap closed.

Similar reference-letters refer to similar parts in the different views.

Our invention relates to that class of envelops known as "merchandise-envelops," 25 having a metallic fastener attached to the body of the envelop and comprising a pair of bendable tongues adapted to pass through an opening in the seal-flap and be bent down upon the outside thereof in order to hold the seal-flap against the body and close the envelop; and our invention consists in the novel 30 features of construction of the metallic fastener and in the application of a flexible stay-strip to the seal-flap surrounding the opening in the seal-flap and extending to the tip of the seal-flap, forming a tab by which the seal-flap is lifted.

The metallic fastener attached to the body 35 A of the envelop consists of a head comprising the two cross-bars A' A², connected together at their central portions by a neck B, from the center of which and integral therewith are the bendable tongues C C', normally 40 projecting in a straight line from the opposite sides of the neck B, as represented by the broken lines C² C', Fig. 2, but capable of being bent so as to bring the tips C³ near each other and in position to pass through an 45 opening D in the seal-flap E of the envelop. Each end of the cross-bars A' A² is provided

with spurs F, Fig. 2, adapted to pass through the body of the envelop and be bent over or clenched upon the inside of the envelop, whereby the metallic fastener is attached to 55 the body of the envelop, as shown in Fig. 2.

The neck B is considerably longer than the width of the bendable tongues C C', so as to leave spaces G between the cross-bars A' A² and the bendable tongues. As the bendable 60 tongues C C' are bent from the position shown by broken lines in Fig. 2 to the position shown by full lines, with the tips C³ C³ in proximity to each other, as shown in Fig. 2, the lower portions of the tongues will be 65 curved, as at C⁴, with the space between the curved portions C⁴ considerably larger than the width of the neck B.

We form an opening D in the seal-flap in proper position to receive the bendable 70 tongues as the seal-flap is folded over against the body of the envelop, said opening D having a diameter slightly in excess of the width of the neck B, so that as the seal-flap is pressed over the bendable tongues and against the body of 75 the envelop the seal-flap will compress the two bendable tongues together as it passes over the curved portion C⁴, and when the seal-flap reaches the body of the envelop, with the opening D just above the neck B of the fastener, the elasticity of the bendable tongues 80 will cause them to spring apart and hold the seal-flap in contact with the envelop while the tongues are being bent down over the seal-flap, as shown in Fig. 5. Instead of inclosing 85 the opening D with a metallic eyelet, as is commonly done in envelops of this class in order to protect the paper from being torn, we reinforce the opening by a strip of canvas or similar woven material H, which is pasted 90 upon the under side of the seal-flap surrounding the opening D and extending substantially to the tip E' of the seal-flap, thereby covering the space between the opening D and the tip E', so that when the tip of the seal-flap is seized by the thumb and finger in order 95 to raise the seal-flap off the fastener in opening the envelop the strain will be applied to the reinforcing-strip H, thereby preventing the seal-flap from being torn.

By employing a woven material for the reinforcing-strip H the edge of the opening D

is left flexible and is capable of adapting itself to the shape of the tongues as it is drawn over them in the operation of closing the envelop, the opening D becoming elongated in a direction transversely to the neck B and contracted in the opposite direction, forming an oblong opening I, as shown in Figs. 4 and 5. When a circular metallic eyelet J is employed to protect the edge of the opening D, the opening requires to be of much greater diameter and leaves an unsightly opening around the bendable tongues C C', whereas in our improved envelop the opening D in the operation of closing the envelop is shaped to and caused to hug closely around the base of the tongues C C'. The seal-flap is thereby held in proximity to the body of the envelop, while the bendable tongues C C' are bent down into the position shown in Fig. 5.

20 When a metallic eyelet is used, the seal-flap has to be held down with one hand while the tongues are bent over with the other.

In opening the envelop the tips C³ of the tongues are slightly raised and the seal-flap 25 E is pulled off by the tip E', the reinforcement H serving as a tab to receive the strain and protect the seal-flap.

What we claim as our invention, and desire to secure by Letters Patent, is—

30 1. A metallic fastener consisting of a sheet-metal plate provided at its corners with attaching-spurs adapted to pass through the body of the envelop and be bent over or clenched upon the inside of the envelop and a pair of bendable tongues integral with said plate and projecting therefrom upon opposite sides of said plate.

35 2. The combination with the body of an envelop, of a fastening device consisting of a plate provided with spurs for the attachment of the plate to the body of the envelop, and a pair of bendable tongues projecting from the opposite sides of said plate, and between said spurs, said plate being slit on opposite sides of said tongues on line parallel with said tongues, whereby the length of said tongues is increased.

40 3. In a merchandise-envelop, the fastening device consisting of a plate provided with at-

taching-spurs F, F and a pair of bendable 50 tongues C, C' said plate being slit on opposite sides of said tongues, on lines parallel with said tongues whereby said tongues are bendable on lines near the center of said plate and said attaching-spurs are bendable on 55 lines farther from the center of said plate, substantially as described.

4. A metallic fastener consisting of a sheet-metal plate provided at its corners with attaching-spurs adapted to pass through the 60 body of the envelop and be bent over or clenched upon the inside of the envelop and a pair of bendable tongues integral with said plate and projecting therefrom upon opposite sides of said plate, each of said tongues being 65 placed midway between the attaching-spurs upon the same side of the plate.

5. A metallic fastener consisting of a sheet-metal plate provided with bendable tongues projecting in opposite directions from the 70 sides of said plate and attaching-spurs formed on the ends of arms extending laterally from the sides of said plate, whereby the resistance offered by said attaching-spurs to the strain incident to the bending of said tongues is increased, substantially as described.

6. A metallic fastener composed of sheet metal, and comprising two cross-bars A', A², connected together at their central portions by a neck B, from the center of which and integral therewith are the bendable tongues C, C', of much less width than the length of the neck and capable of being bent so as to bring the tips C³, near each other and in position to pass through the opening in the flap to be fastened, each cross-bar having a spur F at its outer ends adapted to pass through the body of the envelop and be bent over or clenched upon the inside of the envelop, whereby the envelop-fastener is securely attached to the 90 body of the envelop.

Dated this 31st day of May, 1901.

CHARLES E. CATHER.
LOUIS H. BUCKLEY.
